[57] CLAIM

The ornamental design for the reclosable pouch worn about the waist, as shown and described.

DESCRIPTION

FIG. 1 is a top plan view of a reclosable pouch worn about the waist embodying my new design;

FIG. 2 is a front elevational view of the pouch of FIG. 1;

FIG. 3 is a bottom plan view of the pouch of FIG. 1;

FIG. 4 is a rear elevational view of the pouch of FIG. 1;

FIG. 5 is a right side elevational view of the pouch of FIG. 1, the left side being a mirror image thereof;

FIG. 6 is a front elevational view of a first alternative embodiment of the pouch embodying my new design;

FIG. 7 is a front elevational view of a second alternative embodiment of the pouch embodying my new design;

FIG. 8 is a front elevational view of a third alternative embodiment of the pouch embodying my new design;

FIG. 9 is a top plan view of a fourth alternative embodiment of the pouch embodying my new design;

FIG. 10 is a front elevational view of the pouch of FIG. 9;

FIG. 11 is a bottom plan view of the pouch of FIG. 9;

FIG. 12 is a rear elevational view of the pouch of FIG. 9;

FIG. 13 is a right side elevational view of the pouch of FIG. 9, the left side being a mirror image thereof;

FIG. 14 is a front elevational view of a fifth alternative embodiment of the pouch embodying my new design;

FIG. 15 is a perspective view of the pouch of FIG. 9; and,

FIG. 16 is a perspective view of the pouch of FIG. 2.

The broken line showing of a belt is for illustrative purposes only and forms no part of the claimed design.

It should be known that the individual panels shown in each drawing can be decorated with colors, logos, designs and the like.
